UNITED STATES PATENT OFFICE.

SWITS CONDÉ, OF OSWEGO, NEW YORK.

DESIGN FOR A KNIT FABRIC.

SPECIFICATION forming part of Design No. 12,764, dated February 14, 1882.

Application filed December 12, 1881. Term of patent 7 years.

To all whom it may concern:

Be it known that I, SWITS CONDÉ, of Oswego, in the county of Oswego, in the State of New York, have invented new and useful Improvements in Design for Knit Fabric, of which the following, taken in connection with the accompanying drawing, is a full, clear, and exact description.

This design consists in a peculiar and tasteful arrangement of a series of straight and parallel wide mottled stripes of equal widths, and narrow plain dark stripes and plain light stripes arranged alternately between the mottled stripes.

Referring to the annexed drawing, *a a* are the wide mottled stripes of equal widths, and *b* and *c* denote the narrow plain dark stripe and plain light stripe, respectively.

What I claim is—

The design for knitted fabric, consisting of a series of straight and parallel wide mottled stripes, *a a*, of equal widths, and narrow plain dark stripes *b* and plain light stripes *c*, arranged alternately between the aforesaid mottled stripes, substantially as set forth and shown.

In testimony whereof I have hereunto signed my name and affixed my seal, in the presence of two attesting witnesses, at Oswego, in the county of Oswego, in the State of New York, this 1st day of November, 1881.

SWITS CONDÉ. [L. S.]

Witnesses:

EDW. MAXWELL,
F. W. TITUS.
